UNITED STATES PATENT OFFICE.

CHARLES D. ORCUTT, OF DAYTON, OHIO.

DESIGN FOR A STOOL-LEG.

SPECIFICATION forming part of Design No. 36,288, dated April 14, 1903.

Application filed July 14, 1902. Serial No. 115,602. Term of patent 3½ years.

To all whom it may concern:

Be it known that I, CHARLES D. ORCUTT, a citizen of the United States, residing at Dayton, in the county of Montgomery and State 5 of Ohio, have invented a certain new and ornamental Design for a Stool-Leg; and I do declare the following to be a full, clear, and exact description of the invention, such as will enable others skilled in the art to which it applies to make and use the same, reference being had to the accompanying drawings, and to the letters of reference marked thereon, which form a part of this specification.

Figure 1 is a side elevation of a stool-leg, 15 showing my new design. Fig. 2 is a front elevation. Fig. 3 is a top plan view.

As shown in the accompanying drawings, the leading or material features of my design consist in confining the surface ornaments 20 of the leg to the upper portion thereof and in constructing the upper portion of the leg from a point adjacent to the center thereof much wider than the lower portion of said leg, so that the leg viewed as a whole will 25 have the appearance of a long narrow body which terminates at its upper end in a substantial width or a width approximating four times the width of the leg below the center. The leg has two degrees of curvature extend-

ing in opposite directions, as at A and B. 30 The outer surface of said leg is provided with two plain marginal bars C C, which curve outwardly and terminate at their upper end in clusters of curved figures D. Within these marginal bars C and upon the upper 35 half of the leg there are provided two clusters of ornamentalations F F, consisting of irregular figures. These two clusters F F are separated in the center of the leg by a bar G, which terminates at its upper end in a fork 40 or spreading members. The lower half of the leg is provided with a central panel or bar E, which extends downwardly to a point above the foot. The upper portion H of the leg is projected in a horizontal direction and 45 is provided with spurs I I.

Having described my invention, what I claim as new, and desire to secure by Letters Patent, is—

The ornamental design for a stool-leg as 50 herein shown and described.

In testimony whereof I affix my signature in presence of two witnesses.

CHARLES D. ORCUTT.
